Primary Examiner — Michael C Stout*Assistant Examiner* — Fitzgerald L Butac(74) *Attorney, Agent, or Firm* — Smith, Gambrell & Russell, LLP(57) **CLAIM**

The ornamental design for a stirrer, as shown and described.

DESCRIPTIONFIG. 1 shows a perspective view of the stirrer;
FIG. 2 shows a top plan view of the stirrer, with the bottom plan view being the same;

FIG. 3 shows a front elevation view of the stirrer, with the rear elevation view being the same;

FIG. 4 shows a right side end view of the stirrer; and,
FIG. 5 shows a left side end view of the stirrer.

The broken lines seen in FIGS. 1-4 show portions of a stirrer that form no part of the claimed design.

The broken line with varying lengths seen in FIGS. 1, 2, 3, and 5 show the bounds of the claimed design, and form no part thereof.
